DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

PROGRAM TEST METHOD

Richard Anthony Bender, Hyde Park, and Earl Lee Pottorff, Poughkeepsie, N.Y., assignors to International Business Machines Corporation, Armonk, N.Y.
Continuation of application Ser. No. 249,650, May 2, 1972. This application Mar. 25, 1974, Ser. No. 454,047
Int. Cl. G06f 11/04, 9/06; G05b 17/02
U.S. Cl. 444—1

26 Sheets Drawing. 127 Pages Specification

A method of analyzing computer programs which are to be tested. The method determines the data flow patterns through a program and uses the data flow patterns to identify a set of paths in the program which must be exercised in order to verify a program's correctness. The method includes the steps of: partitioning the program source statements into groups (each of which always executes as a serial unit, i.e. serial), determining the execution sequences of the different serial units, determining the data input and output activities of the serial units across their boundaries and the program boundaries, locating the sources of input data to each serial unit, and identifying test paths through the program such that every first-order dependency (each direct source of an input data item provided to each serial unit) is exercised by test data designed to exercise this set of test paths. The method can be applied to programs written in different programming languages.
